UNITED STATES PATENT OFFICE

2,669,980

TWO-CYLINDER CRANKCASE COMPRESSION ENGINE

Harold E. Yarrington, Eau Claire, Wis., assignor
to National Presto Industries, Inc., a corpora-
tion of Wisconsin

Application May 13, 1952, Serial No. 287,488

3 Claims. (Cl. 123—73)

1

The present invention relates to connecting rods and particularly to connecting rods for two-cycle internal-combustion engines.

In two-cycle internal-combustion engines having crankcase compression, an inlet valve admits a fuel-oil-air mixture to the crankcase of the engine on the compression or up stroke of the piston. On the power or down stroke of the piston, the mixture in the crankcase is compressed, and when the piston moves down far enough to uncover the intake port in the side of the cylinder block, the compressed mixture flows from the crankcase through a transfer passage along the side of the block and into the cylinder through the uncovered intake port. To insure proper compression and flow of the mixture, it is desirable to keep the volume of the crankcase as small as possible so as to obtain as high a pumping efficiency from the piston as possible.

In engines of the character defined, the transfer passage on a single cylinder engine may be disposed along the upper side of the piston, the lower side of the piston, the low pressure side of the piston, or the high pressure side of the piston. In a two cylinder engine, the transfer passage is usually located along either the low pressure side of the piston or the high pressure side thereof. In clarification of the foregoing, the high pressure side of the piston is the side which is under pressure from connecting rod angularity during the power stroke, and the low pressure side is the side that is under pressure due to connecting rod angularity during the compression stroke. By providing the transfer passage along the high pressure side of the cylinder block, the high pressure side of the block is cooled by fuel transfer and more uniform cylinder temperatures are obtained. In addition, with the transfer passage along the high pressure side, the circulation inside the crankcase from the rotating crankshaft is then in such direction as to tend to throw the fuel-air mixture outward into the transfer passage, thus theoretically increasing the horsepower output of the motor. Actual testing indicates that this effect is appreciable. From the foregoing, it will be apparent that with the transfer passage on the high pressure side, the connecting rod also swings through the crankcase towards the transfer passage and thus should also tend to move the fuel-air mixture towards the transfer passage.

It is an object of the present invention to increase the normal efficiency and horsepower output of two-cycle internal-combustion engines by

2

increasing the fuel transfer efficiency thereof. Specifically, it is an object of the invention to increase the tendency of the engine connecting rod to throw the fuel-air mixture toward the transfer passage in the engine block.

Another object of the present invention is to accomplish the foregoing specific object of the invention by providing an improved connecting rod for engines of the character defined.

10 Heretofore, engine connecting rods have been designed according to a set pattern wherein the rod comprises a pair of relatively enlarged bosses or heads and a relatively narrow shank of H-shaped cross-section connecting the heads. 15 Very little attention has been paid to the connecting rod design, except that the same fit the engine and be adapted to carry the necessary load. The improved connecting rod of the present invention has some similarity to conventional rods except that the bosses and shank thereof are made as broad or as wide as possible. In particular, the crankshaft or crankpin boss of the rod is designed to fill as closely as possible the space between the crankshaft throws or webs and at least one web of the shank is broadened to substantially the same width as the boss. By increasing the width of the rod, the present invention provides for slight decrease in crankcase volume and for an increased fuel throwing characteristic. While the decrease in crankcase volume accomplished according to the invention is slight, the same is a step in the right direction so that the increased fuel throwing characteristic is not attained as a result of sacrificing crankcase compression.

30 In accordance with the foregoing, it is an object of the present invention to provide an improved connecting rod comprising a pair of bosses and a shank connecting the bosses, the shank having at least one web of a width substantially equal to that of one of the bosses. It is preferred that a single wide web be provided and that the wide web be disposed to the high pressure side of the piston so as to best enhance the fuel throwing characteristic of the rod.

40 45 A further object of the invention is the provision of an improved connecting rod of economical design, manufacture and assembly.

The present invention has the advantage, among others, of providing a definite horsepower increase, particularly at higher speeds, for two-cycle internal-combustion engines, without unduly increasing the cost of the engine.

50 Other objects and advantages of the present invention will become apparent in the following

detailed description of a preferred embodiment of the invention, wherein reference is made to the accompanying drawings, in which:

Figure 1 is a cross sectional view of a two-cycle internal-combustion engine including the connecting rod of the present invention;

Figure 2 is a vertical section of one cylinder of the engine, the view being taken substantially on the line 2-2 of Figure 1 and showing the connecting rod of the present invention in side elevation; and

Figure 3 is a cross-sectional view of the connecting rod of the present invention, taken substantially on the line 3-3 of Figure 2.

While the present invention has particular adaptability to two-cycle internal-combustion engines, and is described herein as incorporated in a two cylinder two-cycle engine, it will be apparent as the description proceeds that the present invention is applicable to other types of engines. For example, the present invention is applicable to engines provided with crankcase lubricating systems, wherein lubricant is forced or fed to moving parts of the engine by means of crankcase compression and/or the eccentric throw of the engine connecting rods and crankshaft.

Referring now to the drawings, the present invention is shown as incorporated in a motor of the general type disclosed in Patent No. 2,289,201 and Patent No. 2,507,034, both issued to George W. Martin. As shown in Figure 1, the motor or engine comprises a two cylinder, two-cycle internal-combustion engine including a cylinder block, indicated generally at 10 defining a pair of cylinders 12 and a pair of crankcases 14. Each of the crankcases 14 is provided with a port, not shown, in communication with an intake manifold 16 to which a fuel-oil-air mixture is fed from a carburetor, not shown. The ports in the crankcases 14 are each controlled by means of a valve, not shown, adapted to be actuated by means of a lever 18 pivoted on a shaft 19 and engaging an eccentric 20 on or carried by the engine crankshaft 22. The crankshaft 22 is journaled in the body or block 10 and is rotatably supported therein at its opposite ends by means of suitable roller bearings 24 or the like. The crankshaft 22 is provided adjacent its outer ends with conventional oil seals 26 which seal the respective crankcases 14 from atmosphere. Intermediate its ends, the crankshaft 22 is rotatably supported by a metallic block or plug 28 which comprises a bearing for the crankshaft and also constitutes a seal between the two crankcases 14.

The crankshaft 22 is a continuous unitary shaft having a pair of eccentric throws 30, one disposed in each of the crankcases 14. The eccentric throws 30 each comprise a pair of spaced webs 32 and a crank pin 34 extending between the webs 32 and disposed eccentrically of the axis of rotation of the crankshaft 22. The crank pins 34 are each adapted for the reception of and rotatably support the head or crank pin end or boss 36 of a connecting rod 38. The connecting rods 38 may be formed in any desired manner such as by being cast. Preferably, however, each rod comprises an integrally forged member including the head or boss 36, a wrist pin boss 40 and a shank 42 connecting the bosses 36 and 40. The wrist pin boss 40 is rotatably journaled on a tubular wrist pin 44 of a piston 46. If desired, the bosses 36 and 40 may be journaled on the pins 34 and 44 by means of suitable bushings 48 and 50, respectively. The pistons 46 are conventional in design and are adapted for reciprocal movement in the cylinders 12. If desired, the

cylinders 12 may be each provided with a conventional cylindrical liner 52.

Referring now to Figure 2, the cylinder block or body 10 and the cylinder liners 52 are each provided with an intake port 54 leading into each of the cylinders 12, a fuel passage 56 extending between the intake port 54 and the respective crankcase 14, an exhaust port 58 and an exhaust manifold 60. The construction of the engine as thus far described is substantially conventional in all respects and the operation of the engine is likewise conventional. Referring to Figure 1, the piston shown at the left of the figure is about to commence its upward or compression stroke, as is the piston shown in Figure 2. After the piston has been moved upwardly a short distance so as to close the intake port 54, the eccentric or cam 20 is adapted to move the lever 18, in the left-hand crankcase 14 of Figure 1, to open the respective valve and accommodate entry of the fuel mixture, which is sucked into the crankcase on the compression or up stroke of the respective piston 46. As the piston 46 approaches its top dead center position, or approximately at this position, the compressed charge contained in the cylinder above the piston is ignited and the piston commences its downward power or expansion stroke. The inlet valve is closed during the first portion of the piston power stroke, preferably, at from 30° to 60° beyond top dead center position of the piston. Accordingly, as the piston performs the remainder of its power stroke, as will be appreciated from a consideration of the piston shown at the right in Figure 1, the fuel-air mixture within the crankcase 14 and beneath the piston 46 will be compressed by the piston until the piston is moved downwardly to an extent sufficient to uncover the intake port 54, at which time the compressed fuel-air mixture is forced or will flow into the cylinder 12 above the piston 46. As will be apparent from Figure 2, the piston 46, due to its design, comprises a baffle adapted to properly direct the entering fuel-air mixture throughout the cylinder 12 to effectively scavenge the cylinder and effect exhaust of the combustion products in the cylinder through the exhaust port 58 and the exhaust manifold 60. Thereafter, the piston 46 again commences its upward movement to close the intake port 54, at which time the proper valve is again opened by the respective eccentric or cam 20 and the operation described is repeated. As will be apparent from Figure 1, the two eccentric throws of the crankshaft 22 are disposed substantially diametrically opposite one another so that the compression stroke of one piston is effected during and by the power or expansion stroke of the other piston, so that the two pistons will operate to provide or impart a constant driving force to the crankshaft 22.

In view of the foregoing description, it will be appreciated that the fuel-air mixture is fed to the various cylinders under compression during the power stroke of the respective piston. In accordance with conventional engine design, it will be appreciated that engine efficiency may be increased by increasing the effectiveness of the intake flow and by increasing the compression of the engine. To effectively increase the degree of compression of the fuel-air mixture, the volume of the crankcase should be maintained as small as possible, with the limiting factor of maintaining sufficient volume in the crankcase to supply a full charge of fuel-air mixture to the cylinder. However, since sufficient room must be provided in the crankcase for the rotation of the eccentric

throw of the crankshaft and for the movement of the connecting rod, optimum fuel compression conditions are not readily obtained. To provide for high engine efficiency, the eccentric throws for the crankshaft include webs 32 of such volume as to substantially fill the crankcase and thus decrease the volume thereof. As will be noted from Figure 1, the webs 32 of the crankshaft throws fit closely within the confines of the crankcase 14 and the crankcases 14 are of relatively foreshortened height so that the crankshaft webs extend partially into the cylinder liners to thus reduce crankcase volume to a minimum.

To further increase engine efficiency, it will be noted from Figure 2 that if crankshaft and connecting rod rotation be in the direction indicated, the fuel-air mixture will be forced, due to the rotation of the crankshaft and connecting rod, in the direction of the intake passage 56. To maintain the relationship described, and as shown in Figure 2, the intake passage 56 and the intake port 54 are disposed to the high pressure side of the piston 46, that is, to the side of the cylinder against which the piston exerts pressure during the power stroke of the piston. Due to the angularity of the connecting rod 38, the piston will exert pressure on opposite walls of the cylinder on the opposite strokes thereof. Considering Figure 2, connecting rod angularity is downward and to the right, on the power stroke, thus forcing the piston to the left and against the intake side of the cylinder.

While the foregoing features result in increased engine efficiency, it is an object of the present invention to still further increase efficiency by effecting a slight decrease in crankcase volume and by substantially increasing the fuel throwing action of the crankshaft and connecting rod in an extremely economical and convenient manner. To accomplish this particular object, the present invention provides an improved connecting rod or an improved connecting rod feature adapted to be incorporated in conventional connecting rods. Referring to the drawings, the rod shown therein is conventional in substantially all respects and comprises the cylindrical wrist pin boss 40, the cylindrical crank pin boss 36 and the shank 42. The crank pin boss 36 is preferably formed integrally with the remainder of the connecting rod and is thereafter fractured or cut transversely so as to provide a saddle portion 62 integral with the shank 42 and a cap 64 adapted to be detachably secured to the saddle 62 by means of a pair of bolts 66 extending through the side lugs 68 of the boss or head. The shank of the connecting rod generally may be considered as conventional with the exception of the provision of an extremely wide web 70 on at least one side of the shank. Conventional shanks of internal-combustion engine connecting rods have a generally I-shaped cross section and comprise a central portion and two webs of substantially reduced width with respect to the bosses of the rod, the webs generally being of approximately the size of the web indicated at 72 in Figure 3. According to the present invention, the connecting rod shank includes a broadened web of substantially the same width as the bosses of the rod so that the rod presents, when viewed in front elevation as shown in Figure 1, a substantially uniform width throughout its full length. The provision of the wide web 70 substantially increases engine efficiency as will be pointed out hereinafter without presenting any substantial

increase in the cost of fabrication of the connecting rod. The web 70 is preferably of a width substantially equal to the width of at least the crank pin boss of the connecting rod so that the same may be conformably received within the space between the webs 32 of the crankshaft throws and extends from the crank pin boss toward the wrist pin boss. Preferably, the web 70 is continuous and merges with both bosses at its opposite ends. In cases where one of the connecting rod bosses is wider than the other, the web 70 at its opposite ends may be of substantially the same width as the adjacent boss and may taper or have other suitable configuration between its ends. Preferably, the connecting rods formed according to the present invention have wrist pin bosses and crank pin bosses of substantially equal width and webs of substantially the same width extending throughout the length of the connecting rod. If desired, the rod may include two wide webs, such as the web 70, so that the connecting rod shank is of substantially I or H-shape in cross section. However, to decrease the amount of material required in the connecting rod, to decrease the weight of the rod and to minimize the cost of fabricating the rod, it is preferable to provide a single web 70 so that the connecting rod shank is of generally T-shape in cross section, as is shown in Figure 3.

In construction, the crankpin boss 36 and the lugs 68 thereof are preferably formed of a size to substantially fill the space between the webs of the crankshaft throws and, as stated, the web 70 is formed of substantially the same width as the boss 36. Accordingly, the connecting rod of the present invention provides for a slight decrease in crankcase volume and a substantial increase in the fuel throwing characteristic of the rod. To further enhance these features, the present invention contemplates the provision of a groove 74 in each of the crankcases 14 to accommodate the connecting rod. Referring to the drawings, it will be appreciated that portions of the crankpin boss 36 protrude from the margins of the crankshaft throws during operation of the engine. Rather than form the entire crankcase of a size to accommodate the rotation of the crankpin boss, the crankcase, in accordance with the present invention, is formed in the major portion thereof to accommodate only the crankshaft webs, and at the portion thereof within which the crankpin boss moves, a groove 74 is provided to accommodate the crankpin boss. Such construction results in a further slight decrease in crankcase volume and, in addition, provides a trench or the like to concentrate the accumulation of fuel-air mixture in the path of rotation of the connecting rod. As will be apparent from Figure 2, the trench or groove 74 leads directly into the fuel transfer passage 56.

In use and operation of the connecting rod of the present invention, the rod is mounted on the wrist pin 44 and the crank pin 34, as is shown in Figure 2, with the broad web 70 thereof disposed to the high pressure side of the piston, which, in accordance with the present invention, is to the intake passage side of the crankcase and cylinder. In operation, the enlarged or widened web 70 of the improved connecting rod, as the same is rotated in the direction indicated by the arrow in Figure 2 toward the intake passage 56 when the intake port 54 is open, presents a broad surface adapted to engage the fuel-air mixture in the crankcase 14 so as to throw or force the fuel-air mixture toward the

passage 56. The groove 74 in each crankcase serves to accumulate the fuel-air mixture in the path of the rod to enhance the fuel throwing action. As will be appreciated from Figure 2, and conventional engine design, the intake port 54 is maintained open during approximately 100° of movement of the crank pin 37 and the crank pin boss 36 of the connecting rod; that is, approximately 50° to either side of the bottom dead center position shown in Figure 2. Accordingly, the wide web 70 of the connecting rod has adequate swing to effect a throwing action of the fuel-air mixture within the crankcase 14 and the groove 74.

From the foregoing, it will be appreciated that the improved connecting rod and associated features of the present invention provide for increased engine efficiency, particularly at high speeds, and that the widened web 70 of the improved connecting rod provides a super-charging action for internal-combustion engines of the character described and for like apparatus. It will also be appreciated that the present invention provides for increased engine efficiency, in the form of increased horsepower output, particularly at high speeds, without particularly increasing the cost of the engine so that the improvements provided by the present invention are economically obtained.

In its preferred embodiment, as described hereinbefore, the improved connecting rod of the present invention comprises a unitary casting or forging having the broadened or wide web 70 formed integrally with the rod. However, the improved fuel throwing characteristic provided by the invention may be readily accomplished simply by securing a sheet metal plate to the appropriate web of a conventional connecting rod. For example, with a conventional connecting rod having both webs of the size of the web 72 shown in Figure 3, a flat sheet metal plate, of the same width as the bosses 36 and 40 and of a length substantially equal to the distance between the bosses, could be secured, preferably welded, to one of the shank webs so as to present a broad surface, as does the web 70; and, thus, to provide the improved feed throwing characteristic. Accordingly, terms such as "the shank web being of the same width as the connecting rod bosses" as used herein and in the appended claims are to be considered as including not only the unitary forging as shown in the drawings, but such further built-up structures as described immediately hereinbefore.

While I have described what I regard to be a preferred embodiment of my invention, it will be apparent that certain modifications and changes may be made therein without departing from the scope of the invention, as defined by the appended claims.

I claim:

1. A two-cycle internal-combustion engine comprising an engine block defining a plurality of engine cylinders and a crankcase for each of said cylinders, a piston mounted for reciprocation in each of said cylinders, a crankshaft journaled in said block and having an eccentric throw including a pair of webs and a crank pin in each of said crankcases, a fuel manifold adjacent said

crankcase, each of said crankcases having a port communicating with said manifold, and a connecting rod for each of said pistons operatively connecting said pistons to the respective crank pins, said block defining an intake port for each of said cylinders to the side of the cylinder against which the respective piston exerts pressure during its power stroke, said block defining a fuel passage for each of said cylinders extending from the respective intake port to the respective crankcase, each of said connecting rods including a head adapted for engagement with the respective crank pin and adapted to substantially fill the space between the respective crankshaft webs; each of said connecting rods including a shank having a web of substantially the same width as said head disposed in the intake port side of the respective cylinder and crankcase.

2. In a two-cycle internal-combustion engine having a crankcase, compression, a crankcase, a crankshaft having laterally extending webs and a crank pin connecting said webs, a piston having a wrist pin, a connecting rod having a wrist pin boss journaled on said wrist pin, a crank pin boss journaled on said crank pin and a shank connecting said bosses, and a fuel transfer passage disposed to the high pressure side of said piston, said crank pin boss being of a width to substantially fill the space between said crankshaft webs, said shank including a continuous web of substantially the same width as said crank pin boss extending between said bosses, said web of said shank being disposed to the high pressure side of said piston, wherein the engine crankcase throughout the major portion thereof is of a size to accommodate rotation of said crankshaft webs and is provided at the portion thereof in the area of said connecting rod with a groove to accommodate rotation of said crank pin boss.

3. A two-cycle internal-combustion engine according to claim 1, wherein each of said crankcases is of a size throughout the major portion thereof to accommodate rotation of the respective crankshaft webs but not the rotational movement of the respective connecting rod head, each of said crankcases being provided at the portion thereof within which the respective connecting rod moves with a groove accommodating the rotational movement of the respective connecting rod head, each of said grooves leading into the respective fuel passage.

HAROLD E. YARRINGTON.
